UNITED STATES PATENT OFFICE.

LOUIS H. MAIER, OF NEW YORK, N. Y.

AUTOMATIC MUSIC-SHEET TRACKER.

1,183,218.

Specification of Letters Patent.

Patented May 16, 1916.

Application filed October 20, 1911. Serial No. 655,701.

To all whom it may concern:

Be it known that I, LOUIS H. MAIER, a citizen of the United States, and resident of New York city, borough of the Bronx, in the county of New York and State of New York, have invented certain new and useful Improvements in Automatic Music-Sheet Trackers, of which the following is a specification.

10 The object of my invention is to provide improved means to cause music sheets in automatic musical instruments to properly pass over the orifices of the tracker board to the end that the openings in the music sheet shall properly register with the orifices of the trackerboard.

In carrying out my invention I provide a plurality of openings in the trackerboard adjacent any desired number of orifices of 20 the trackerboard, one of such openings for each of such desired orifices being in communication with a pneumatic mechanism and the companion opening being in communication with another pneumatic mechanism, which pneumatic mechanisms are connected with means for operating the music spool or tracker for moving the same back and forth as required to cause the openings in the music sheet to properly 25 register with the orifices of the trackerboard, the arrangement being such that when one or more openings in the music sheet properly register with one or more orifices of the trackerboard, the music spool 30 will be retained in proper tracking position.

My invention further comprises novel details of improvement and combinations of parts that will be more fully hereinafter set forth and then pointed out in the claims.

40 Reference is to be had to the accompanying drawings forming part hereof, wherein,

Figure 1 is a partly sectional face view of music sheet mechanism embodying my invention; Fig. 2 is an enlarged face view of 45 a portion of the trackerboard; Fig. 3 is a portion of the line 3, 3, in Fig. 2; Fig. 4 is a section on the line 4, 4, in Fig. 2; Fig. 5 is a section on the line 5, 5, in Fig. 3, partly broken away; Fig. 6 is a partly sectional view of a modified form of pneumatic mechanism; and Fig. 7 is a partly sectional view illustrating a movable tracker.

Similar numerals of reference indicate corresponding parts in the several views.

55 The trackerboard 1 may be mounted in a frame 2 in any well known manner, which

tracker has usual note orifices 1^a. The music spool 3 carrying the music sheet 4 is mounted in frame 2 in any well known manner, to have longitudinal adjustment. 60 I have shown a slideable spindle 5 pressed by a spring 6 into engagement with one end of spool 3, and at 7 is a slideable spindle engaging the opposite end of spool 3. At 8 is an eccentric shown pivotally supported 65 upon frame 2, as at 9, and provided with an arm 10 to be operated by suitable means, such as opposing pneumatics 11, 12. For this purpose I have shown an arm 10 connected by a rod 13 with a lever 14 pivoted 70 upon frame 2 at 15 and connected by a link 16 to the movable board of pneumatic 11, rod 17 connecting the movable boards of both pneumatics, whereby when one of the 75 movable boards of one pneumatic or the other is collapsed eccentric 8 will be turned to cause spool 3 to be moved to the right or left as the case may be, by the coaction of spring 6 through spindle 7 with said eccentric. At 18 is the takeup spool for the music 80 sheet 4, which spool is shown mounted upon spindle 19 journaled upon frame 2, and which may be rotated in any well known manner. The parts so far described illustrate suitable means for adjusting spool 3 85 lengthwise, but it will be understood that other well known means for this purpose may be used, if desired.

Adjacent one or more of the orifices 1^a of the tracker are pairs of openings a, b, suitably formed in the tracker, which openings a communicate with a channel c in the tracker, and the openings b communicate with a channel d in the tracker. The pairs of openings a, b, are so located with respect 95 to their corresponding tracker note orifices 1^a that the openings or apertures 4^a of music sheet 4 will, when the music sheet properly tracks across the trackerboard orifices 1^a to fully open the latter, also fully open the 100 corresponding pairs of openings a, b, yet if the music sheet should shift or swerve from one side or the other with respect to the tracker orifices 1^a, and thereby close one or more openings a or b, then the music 105 spool will be caused to shift to the right or left to shift the music sheet to the proper normal position, or the tracker will be correspondingly shifted for a similar purpose. To this end the channel c is connected by a 110 tube or pipe 20 with the pouch or pocket 21 of pneumatic 11, and the channel d is like-

- wise connected by tube or pipe 22 with the pouch or pocket 23 of pneumatic 12. Suction for the pneumatics is provided by the pipe 24 connected with any well known exhaust apparatus. Channels *c*, *d*, may be formed in the trackerboard by milling the same with a suitable cutter, the outer portions of the channels being closed by strips *c'*, *d'*, respectively.
- 10 In Fig. 1, when atmospheric pressure enters pouch 21 through pipe 20, valve 21^a will be lifted allowing atmosphere to pass under the valve, thence through pipe 21^c and under the pouch 21^d, raising valve 21^e, thereby opening communication between the pneumatic and pipe 24; and a similar action takes place with respect to the pouches, valves, etc., of pneumatic 12 when atmosphere is admitted to pipe 22.
- 15 In Fig. 6, when atmosphere enters pouch 21 through pipe 20, valve 21^f rises, permitting suction through pipe 21^g to cause pouch 21^d to be drawn down allowing valve 21^e to close the suction from pneumatic 11 and permit atmosphere to enter the same through opening *x*; and similar action takes place with respect to the valves and pouches of pneumatic 12. Thus, the action is opposite to that of Fig. 1, viz: when a pair of openings *a*, *b*, are open to atmosphere, neither pneumatic 11 or 12 will then have suction, but both will be opened to atmosphere.
- 20 In the normal positions of the parts according to Figs. 1 to 5, when the music sheet properly tracks across the tracker, so that one or more of its openings 4^a registers with one or more of the orifices 1^a, and with the companion openings *a* and *b*, as the case may be, pneumatics 11, 12 will both be under exhaust and thereupon music spool 3 will be maintained in the proper position. If, however, the music sheet shifts or swerves, as to the right, so as to cover one or more of the openings *a*, (and leave open the corresponding opening *b* and part of orifice 1^a) and thus stop the flow of air from such opening *a* to the pouch 21 of pneumatic 11; thereby cutting off exhaust from pneumatic 11, the exhaust then present in pneumatic 12 causes its movable board to collapse and push rod 17 to the right in Fig. 1, thereby drawing rod 13 to the left and causing eccentric 8 to push spindle 7 and thereby spool 3 to the left, and thus shift the music sheet to the left to cause the aforesaid opening *a* to open to atmosphere through the corresponding note opening 4^a in the music sheet; whereupon both openings *a* and *b* and the corresponding orifices 1^a will thereupon be properly opened and the music sheet will be retained in such set position, by the neutral action of exhaust in both pneumatics, and the music sheet will continue to properly track until again shifted or swerved to the right or left, and so on. Likewise, if the

music sheet should have shifted or swerved to the left in Fig. 1, so as to cover one or more of the openings *b* (leaving open the corresponding opening *a* and part of orifice 1^a) and thus stop the flow of air from such opening *b* to the pouch 23 of pneumatic 12, thereby cutting off exhaust from pneumatic 12, the exhaust then present in pneumatic 11 causes its movable board to move to the left in Fig. 1; said movable board then pulls 75 upon link 16 and shifts rod 13 to the right, causing eccentric 8 to move in such manner that spool 3 will, by spring 6, be shifted to the right until the corresponding opening *b* is opened to the atmosphere by the corresponding note opening 4^a in the music sheet; and thereupon as the corresponding orifice 1^a and companion openings *a*, *b*, are thus again opened to atmosphere the neutral action of the exhaust in both pneumatics 80 maintains the parts in such position and the music sheet will continue to properly track until again shifted or swerved to the right or left, whereupon similar actions will take place, and so on.

90 While it will be understood that pairs of openings *a*, *b*, may be placed adjacent each tracker orifice 1^a, yet such pairs of openings may be located adjacent any desired orifice 1^a, as, for instance, adjacent the tracker orifices 1^a that are determined to be more frequently used than others.

Instead of shifting the music spool 3 for the purposes above set forth, I have shown means whereby the tracker-board 1 may be 100 shifted to the right or left for the same purpose. To this end the tracker may be mounted for endwise adjustment and connected with the pneumatics 11, 12, as illustrated in Fig. 7. I have shown tracker 1, 105 provided with supports 1^b slidable in frame 2, and connected by a link 25 with lever 14, operated by pneumatics 11, 12, in manner before described. The pairs of openings *a*, *b*, for the desired tracker orifices 1^a are connected with the pneumatics as before set forth. When the music sheet is properly tracking and the tracker is in the normal position; then opening 4^a in the music sheet will uncover an orifice 1^a and its companion 110 openings *a*, *b*, and both pneumatics will then be under exhaust and will maintain the tracker in such set normal position. If, however, the music sheet shifts or swerves, as to the right, so as to cover one or more 115 openings *a*, and thus stop the flow of air from such opening to the pouch 21 of pneumatic 11, thereby cutting off suction from pneumatic 11, the suction in pneumatic 12 will push rod 17 to the right and through lever 14 and link 25 the tracker will be shifted to the right, thereby causing such opening *a* to be uncovered and opened to atmosphere through the opening 4^a of the 120 music sheet, and thereupon the tracker will 125

125 65 130

be maintained in such position by the balancing of suction in the pneumatics 11, 12; likewise, if the music sheet should have shifted or swerved to the left in Fig. 7 an 5 opening *b* would be closed and the companion opening *a* left open, whereupon suction will be discontinued from pneumatic 12 and the exhaust in pneumatic 11 will cause lever 14 to be shifted to the left, thereupon 10 shifting the tracker to the left and uncovering such opening *b*, as well as the companion opening *a*, and thereupon the balancing of exhaust in the pneumatics 11, 12 will cause the tracker to be maintained in such 15 position.

In both cases described, when all of the orifices 1^a and all of the openings *a*, *b*, are closed by the music sheet the position of the music sheet or tracker, as set by reason 20 of the action of the pneumatics caused by the tracking of the music sheet with respect to the last opening 4^a of the music sheet that coacted with an orifice 1^a, will be maintained until another shift of the music spool 25 or the tracker takes place.

Having now described my invention what I claim is:

1. A tracker having note orifices and provided with a pair of openings adjacent one 30 of the tracker orifices and located between the transverse extremes of the latter and between the latter and the longitudinal edge of the tracker, said orifices and openings being in the path of note openings in a 35 traveling music sheet when the latter is in its normal operating position, combined with a pair of pneumatics, controlling means for each pneumatic, means connecting one of said openings with the controlling means 40 of one of said pneumatics, and means connecting the other of said openings with the controlling means of the other of said pneumatics, whereby said pneumatics will be operated according to the passage of air 45 through the corresponding opening, tracking controlling mechanism, and means controlled by said pneumatics for operating said mechanism.

2. A tracker having note orifices and separate channels and provided with pairs of openings each pair adjacent a corresponding orifice and located between the transverse extremes of the latter and between the latter and the longitudinal edge of the tracker, one 55 of the openings adjacent to each orifice communicating with one of the channels, and the other opening adjacent to each orifice communicating with the other channel, said orifices and openings being in the path of note openings in a traveling music sheet 60 when the latter is in its normal operating position.

3. The combination of a tracker adapted to be used with a perforated note sheet, said 65 tracker having an orifice and a pair of open-

ings adjacent the same and located between the transverse extremes of the latter in the path of note perforations in the music sheet, and tracking controlling mechanism held normally set when both of said openings 70 are opened and are closed to atmosphere and operated when one of such openings is open to atmosphere and the other is closed to atmosphere.

4. The combination of a tracker adapted 75 to be used with a perforated music sheet, said tracker having orifices and a pair of openings adjacent one of said orifices and located between the transverse extremes of the latter, and means for maintaining registration of the perforations in the music sheet with the orifices of the tracker when said openings register with perforations in the music sheet.

5. The combination of a tracker adapted 85 to be used with a perforated music sheet, a music spool, said tracker having orifices and a pair of openings adjacent one of said orifices and located between the transverse extremes of the latter, in the path of note 90 perforations in the music sheet, mechanism adapted to shift one of the first two named elements relatively one to another, and means to control the action of said mechanism by air passing through said openings 95 from a perforation in the music sheet, said mechanism serving to shift one of the first named elements when air passes through one of said openings and is prevented by the music sheet from passing through the other 100 of said openings.

6. The combination of a tracker adapted to be used with a perforated music sheet, said tracker being provided with note orifices and having a pair of openings adjacent one of said orifices and located between the transverse extremes of the latter and in the path of note perforations in the music sheet, mechanism to shift one of the first two 105 named elements, and means to control said mechanism operated by air passing through a note perforation in the music sheet to and through one of said openings while the companion opening is closed by the music sheet.

7. The combination of a tracker, a longitudinally adjustable music spool, said tracker having an orifice and a pair of openings adjacent the orifice and located between the transverse extremes of the latter and in the path of note perforations in the music sheet, and mechanism controlled by air passing through said openings and operatively connected with the music spool for maintaining the music spool in normal position when both of said openings are open or closed by the music sheet and for shifting the spool when one of the openings is closed and the other is open to atmosphere through the music sheet.

8. The combination of a tracker, a longi-

itudinally adjustable music spool, said tracker having orifices and a pair of openings adjacent the orifice and located between the transverse extremes of the latter and in the path of note perforations in the music sheet, a pair of pneumatics respectively in communication with one of said openings, and mechanism controlled by said pneumatics for shifting the music spool longitudinally upon one only of said openings being closed by the music sheet.

9. The combination of a tracker, a longitudinally adjustable music spool, said tracker having orifices, and pairs of openings respectively adjacent several of said orifices and located between the transverse extremes of the latter and in the path of note perforations in the music sheet, said tracker also having a plurality of channels, one of said channels being in communication with one opening of each pair of said openings and the other channel in communication with the other of said openings, pneumatics having valve devices respectively connected with said channels, and means operated by said pneumatics for shifting the music spool when one of said openings is closed by the music sheet.

10. A tracker bar for playing attachments for musical instruments making use of a perforated music sheet, said tracker bar being provided with the usual ducts for register with the note slots of a music sheet and said tracker bar being also provided, within the space bounded by two planes passing through the side edges of a tracker duct with two additional openings both located adjacent to one of the end edges of said tracker duct, which end edge extends in the direction of the length of the tracker and said additional openings being in alinement longitudinally of the tracker, substantially as set forth.

11. A tracker bar for playing attachments for musical instruments making use of a perforated music sheet, said tracker bar being provided with the usual ducts for register with the note slots of a music sheet and being also provided with two supplemental openings both pertaining to one and the same music duct in the tracker, said openings being of less dimensions in the direction of the length of the tracker than the music duct to which said openings pertain, and said openings being in alinement in the direction of the length of the tracker, substantially as set forth.

12. The combination of a music sheet containing perforations, with mechanism comprising apertures with which said perforations are adapted to register for the purpose

of producing musical sounds and apertures coacting with said perforations whereby said sheet is automatically adjusted to effect registration of said perforations with said apertures first named, said second named apertures being in communication with said perforations in the normal position of said sheet.

13. The combination of a tracker bar containing a set of apertures for effecting the production of musical sounds, said tracker bar containing channels having respective sets of apertures coöordinated with said apertures first named, a music sheet having perforations coöordinated with said sets of apertures respectively, and pneumatic mechanism having connections with said sheet and channels whereby said perforations are maintained in registration with said apertures first named.

14. The combination of a music sheet containing perforations, with mechanism comprising apertures with which said perforations are adapted to register for the purpose of producing musical sounds, means comprising pneumatically operated devices for shifting said sheet laterally, a suction duct, valve mechanism for controlling communication between said suction duct and pneumatic devices, diaphragms for operating said valve mechanisms, and passages for communicating air pressure communicated through said perforations to said diaphragms.

15. The combination of a music sheet containing perforations with mechanism comprising apertures with which said perforations are adapted to register for the purpose of producing musical sounds, means comprising pneumatic devices for shifting said sheet laterally, a chamber adapted for communication with said pneumatic devices, valve mechanism for controlling said communication, a suction duct connected with said chamber, means comprising chambers connected with said suction duct, passages whereby air pressure communicated through said perforations is conveyed to said chambers second named, and diaphragms between said chamber first named and said chambers second named for controlling said valve mechanism.

Signed at New York city, in the county of New York, and, State of New York, this 18th. day of October, A. D. 1911.

LOUIS H. MAIER.
